FIG. 2.

INVENTOR
by *Thomas Clarkson*,
Watson, Croft, Moore & Grindler

UNITED STATES PATENT OFFICE.

THOMAS CLARKSON, OF LONDON, ENGLAND.

STEAM GENERATOR OR WATER HEATER.

Application filed December 31, 1925, Serial No. 78,672, and in Great Britain January 16, 1925.

This invention relates to steam generators or water heaters of the kind comprising an annular water chamber having short closed-ended tubes or thimbles projecting radially 5 inwards therefrom into a heating space through which hot gases pass. The object of the invention is to provide an improved generator or water heater of this type in which the path followed by the hot gases 10 when flowing through the heating space may be improved and the amount of heat transmitted from the hot gases to the water varied.

According to this invention a tubular 15 member is mounted within the heating chamber with its wall adjacent to the ends of the thimbles, and the inlet passage for the hot gases at one end of the generator is so formed that a circular motion around the 20 tubular member is imparted to the hot gases in addition to their longitudinal motion over the thimbles through the generator. To this end a substantially helical guide surface or passage for the hot gases is conveniently formed in a member at one end of the 25 generator, the axis of the helix preferably being coincident with that of the generator whereby the desired motion is imparted to the gases entering the central heating chamber 30 of the generator.

Preferably a valve or the like is provided whereby part of the hot gases may be bypassed so as not to pass through that part of the central chamber in which the thimbles lie. One way of effecting this is to provide a two way valve in the delivery pipe for the hot gases exterior to the generator whereby the relative amounts of hot gases passing respectively through the generator 35 and through a by-pass passage can be controlled.

In an alternative arrangement the tubular member may act as the by-pass passage, a valve being arranged to control the relative 45 amount of the gases passing respectively through and around the tubular member. In this arrangement the tubular member may itself act as the valve and to this end may be longitudinally movable so as in one 50 position to rest on a member which closes one of its ends so that all the hot gases are caused to pass through the surrounding space in which the thimbles lie, while in another position it closes communication between this space and the outlet passage 55 and itself constitutes the only communicat-

ing passage between the inlet and outlet through which all the hot gases are thus caused to pass. The member on which the tubular member is adapted to rest when all 60 the hot gases are to pass around it is conveniently conical while the gas outlet passage is coaxial with the tubular member and of such diameter that it forms a substantially gas-tight fit with the top of the 65 tubular member when this member is raised. In this way the tubular member acts as a valve by means of which the relative amounts of the hot gases passing through it and through the annular space in which the 70 thimbles lie can be varied as desired.

The invention may be carried out in various ways but two alternative constructions according to this invention are illustrated somewhat diagrammatically by way of example 75 in the accompanying drawings, in which

Figure 1 is a vertical section along the longitudinal axis of one construction of generator in which a separate by-pass valve is 80 provided to vary the amount of gas passing through the heating space of the generator, and

Figure 2 is a similar view of an alternative construction in which the tubular member itself acts both as a by-pass passage through which part of the hot gases may be caused to flow and a valve for controlling the relative quantities of the hot gases flowing respectively therethrough and through 90 the space in which the thimbles lie.

In the construction illustrated in Figure 1 the generator or water heater comprises a substantially annular water chamber built up from two coaxial cylindrical members 95 A and B connected by suitable plates C and C¹ at their upper and lower ends. The inner member B carries a series of short closed-ended tubes or thimbles D projecting radially inwards therefrom into a central 100 space through which the hot gases are adapted to pass and is somewhat reduced at its upper end as shown at B¹ to form an outlet passage for these gases.

The annular water chamber is supported 105 on a base E which conveniently has a lining F of refractory material and contains a plug-like member G, also preferably of refractory material, in which is formed a substantially helical inlet passage G¹ for the hot gases, 110 this passage communicating with a delivery pipe H and also preferably having a liquid

fuel burner indicated at H^1 disposed therein. The helical passage causes the gases to circulate round the central space as they pass through it. The member G has a hollow central boss G^2 adapted to accommodate a plug J^1 on the lower end of a tubular member J mounted in the central space of the generator and of such diameter that its wall lies adjacent to the inner ends of the thimbles D . The tubular member J comprises a lower portion J^2 formed of refractory material and an upper portion J^3 formed of metal. The lower end of the upper portion J^3 fits over the upper end of the lower portion J^2 and is connected thereto by one or more pins or the like J^4 . The upper end of the tubular member J is formed conical and supported by a vertical bolt K , one end of which engages a suitably tapered plug J^5 in the upper end of the member J while the other end engages a bridge piece K^1 extending across the upper end of the outlet passage B^1 .

The delivery pipe H conveniently communicates with a by-pass passage H^2 and interconnected valves L L^1 are provided controlling respectively the passages H and H^2 and adapted to be operated simultaneously by a lever L^2 so as to vary the relative quantities of the hot gases flowing respectively through the generator or water heater and through the by-pass passage H^2 . These valves are so interconnected and arranged that when one is fully open the other is fully closed as shown.

A cylindrical baffle M is conveniently disposed in the water space so as to extend around substantially the whole of that portion of the inner cylindrical member B in which the thimbles D are disposed and thus assist in the circulation of water which will tend to pass up inside the baffle and down outside it. When the apparatus is intended for use as a steam generator a perforated steam collecting pipe N is conveniently disposed in the upper end of the steam and water space as shown.

In the construction illustrated in Figure 2 the steam generator and water heater comprises an annular water space built up from two cylindrical members O P connected by suitable flanges or the like at their upper and lower ends. The inner member P carries a series of short closed-ended water tubes or thimbles Q projecting radially inwards therefrom into a central space through which the hot gases pass and is somewhat reduced at its upper end as shown at P^1 to form an outlet passage for these gases. The annular water chamber rests on a base R having a substantially helical inlet passage R^1 formed therein and communicating with a delivery pipe R^2 for the hot gases and preferably also having a liquid fuel burner indicated at R^3 disposed therein. As in the construction illustrated in Figure 1, the

helical passage causes the hot gases to circulate round the central space as they pass through it.

Mounted in the central space is a longitudinally movable tubular member S open at both ends and of such diameter that its wall lies adjacent to the inner ends of the thimbles. In one position as shown in full lines in the drawing the lower end of this tubular member rests on and is closed by a conical member T mounted on the generator base R so that all the hot gases issuing from the helical passage R^4 are caused to flow through the annular space in which the thimbles Q lie. When the tubular member is raised however its lower end is opened and in its fully raised position its upper end fits within the outlet passage P^1 as shown in dotted lines in the drawing. In this position it will be seen that communication between the annular space in which the thimbles Q lie and the outlet P^1 is cut off so that all the hot gases are caused to flow through the tubular member S . In its intermediate position some of the hot gases pass through the tubular member S and some through the space surrounding it, the relative quantities of hot gases passing through and around the tubular member depending on its position. The tubular member S may be raised and lowered in any suitable way but is conveniently operated by a link S^1 connected to a lifting eye S^2 on the upper end of the tubular member. The lower end of the tubular member S is conveniently steadied when in its raised or an intermediate position by means of a guide member comprising a vertical pin S^3 mounted on the member T and carrying a member S^4 having three radial plates S^5 the outer edges of which freely engage the interior of the lower end of the tubular member S and thus act as a guide to steady this member when it is not resting on the conical member T .

As in the construction shown in Figure 1 a cylindrical baffle plate U is conveniently provided in the annular water space extending around that portion of the inner cylindrical member P carrying the thimbles, this baffle serving to assist the circulation of the water which tends to flow up inside the baffle and down outside it.

In either of the constructions illustrated, where a liquid fuel burner is provided in the helical gas inlet passage, this burner is conveniently disposed so that the hot gases therefrom flow along the helical passage into the central space and may be employed either to supplement the hot gases normally supplied or instead of them.

The apparatus is particularly adapted for utilizing the exhaust gases from a Diesel or other internal combustion engine to generate steam or heat water and, in this case, the liquid fuel burner may be used to supply

heat to the generator before the internal combustion engine is started or when it is out of use.

It is to be understood, however, that the generator or water heater is not in any way limited to use with an internal combustion engine but may be employed to utilize hot gases from other sources for generating steam or heating water, and the details of construction may be varied to suit the particular purpose for which the apparatus is intended without departing from this invention as defined in the claims.

What I claim as my invention and desire to secure by Letters Patent is:—

1. A water heater comprising an annular water chamber surrounding a heating space through which hot gases are adapted to flow, closed-ended water tubes projecting radially inwards from the water chamber into the heating space, a tubular member centrally mounted within the heating space with its wall adjacent to the ends of the water tubes, an inlet passage for the hot gases at the lower end of the water heater so formed that a circular motion around the tubular member tends to be imparted to the gases in addition to their upward motion over the water tubes through the water heater, a central outlet for the gases at the upper end of the water heater, a by-pass passage and a valve adapted to vary the relative amounts of the hot gases which pass respectively through the by-pass passage and through that part of the heating space in which the water tubes lie.

2. A water heater comprising an annular water chamber surrounding a heating space through which hot gases are adapted to flow, closed-ended water tubes projecting radially inwards from the water chamber into the heating space, a tubular member centrally mounted within the heating space with its wall adjacent to the ends of the water tubes, a member at the lower end of the water heater having a substantially helical guide surface formed therein, means for delivering hot gases on to this guide surface whereby a circular motion around the tubular member tends to be imparted to the gases in addition to their upward motion over the water tubes through the water heater, a central outlet for the gases at the upper end of the water heater, a by-pass passage, and a valve adapted to vary the relative amounts of the hot gases which pass respectively through the by-pass passage and through that part of the heating space in which the water tubes lie.

3. A water heater comprising an annular water chamber surrounding a heating space through which hot gases are adapted to flow, closed-ended water tubes projecting radially inwards from the water chamber into the heating space, a tubular member disposed

centrally within the heating space with its wall adjacent to the ends of the water tubes, an inlet passage for the hot gases at the lower end of the water heater so formed that a circular motion around the tubular member tends to be imparted to the gases in addition to their upward motion over the water tubes through the water heater, an outlet for the gases at the upper end of the water heater, and a valve whereby a variable proportion of the hot gases can be by-passed through the tubular member so as not to pass through that part of the heating space in which the water tubes lie.

4. A water heater comprising an annular water chamber surrounding a heating space through which hot gases are adapted to flow, closed-ended water tubes projecting radially inwards from the water chamber into the heating space, a tubular member disposed centrally within the heating space with its wall adjacent to the ends of the water tubes, an inlet passage for the hot gases at the lower end of the water heater, an outlet for the gases at the upper end of the water heater and a valve whereby a variable proportion of the hot gases can be by-passed through the tubular member so as not to pass through that part of the heating space in which the tubes lie.

5. A water heater comprising a water chamber surrounding a heating space through which hot gases are adapted to flow, closed-ended water tubes projecting radially inwards from the water chamber into the heating space, a longitudinally movable tubular member disposed centrally within the heating space with its wall adjacent to the ends of the water tubes, an inlet passage for the hot gases at the lower end of the water heater so formed that a circular motion around the tubular member tends to be imparted to the hot gases in addition to their upward motion over the water tubes through the water heater, a central outlet passage for the gases at the upper end of the water heater, a member on which the lower end of the tubular member can rest so as to close this end of the tubular member and thus cause all the hot gases to flow through the annular space surrounding it in which the water tubes lie, and means for raising the tubular member so as to open its lower end and close communication between the outlet passage in the upper end of the water heater and the space in which the water tubes lie and thus cause all the hot gases to flow through the tubular member as set forth.

6. A water heater comprising an annular water chamber surrounding a heating space through which hot gases are adapted to flow, closed-ended water tubes projecting radially inwards from the water chamber into the heating space, a tubular member

- disposed centrally within the heating space with its wall adjacent to the ends of the water tubes, a member at the lower end of the water heater having a substantially helical guide surface formed therein, means for delivering hot gases on to this guide surface whereby a circular motion around the tubular member tends to be imparted to the hot gases in addition to their upward motion 5
- 10 over the water tubes through the water heater, a central outlet for the gases at the upper end of the water heater, a conical member mounted on the member at the lower end of the water heater and on which the 15 lower end of the tubular member can rest so as to close this end of the tubular member and thus cause all the hot gases to flow through the annular space surrounding it in which the water tubes lie, and means for 20 raising the tubular member so as to open its lower end and close communication between the outlet passage at the upper end of the water heater and the space in which the water tubes lie and thus cause all the hot 25 gases to flow through the tubular member as set forth.
7. A water heater comprising an annular water chamber surrounding a heating space through which hot gases are adapted to flow, closed-ended water tubes projecting radially inwards from the water chamber into the heating space, a longitudinally movable tubular member disposed centrally within the heating space with its wall adjacent to the ends of the water tubes, means for delivering hot gases to the lower end of the water heater, a central outlet passage for the gases at the upper end of the water heater, a member on which the lower end of the tubular member can rest so as to close this end of the tubular member and cause all the hot gases to flow through the annular space surrounding it in which the water tubes lie, and means for raising the tubular member so as to open its lower end and close communication between the outlet passage at the upper end of the water heater and the space in which the water tubes lie and thus cause all the hot gases to flow through the tubular member as set forth. 30 35 40 45 50

In testimony whereof I have signed my name to this specification,

THOMAS CLARKSON.
